UNITED STATES PATENT OFFICE.

EDGAR ALAN CUSTER, OF PHILADELPHIA, PENNSYLVANIA.

MEANS FOR AUTOMATICALLY CONTROLLING THE OPENING AND CLOSING OF TWO-PART CASTING-MOLDS.

No. 898,190.

Specification of Letters Patent.

Patented Sept. 8, 1903.

Application filed February 24, 1908. Serial No. 417,399.

To all whom it may concern:

Be it known that I, EDGAR ALAN CUSTER, a citizen of the United States, residing at the city of Philadelphia, in the county of Philadelphia and State of Pennsylvania, have invented certain new and useful Improvements in Means for Automatically Controlling the Opening and Closing of Two-Part Casting-Molds, of which the following is a specification.

My invention has relation to means for automatically controlling the opening and closing of two-part casting molds adapted particularly for employment in a system of casting metal pipe forming the subject-matter of Letters Patent granted to me under date of November 12th, 1907, and numbered respectively, 870,817 and 870,870; and in such connection it relates to the manner of automatically closing the respective molds mounted at suitable distances apart upon a turntable for introducing molten metal thereto from a cupola furnace in the formation of the pipe or other cast structures and thereafter of automatically opening the two-part casting mold sufficiently to permit of ready withdrawal of the cast structures therefrom.

The nature and scope of my present invention will be more fully understood from the following description taken in connection with the accompanying drawings, in which

Figure 1 is a top or plan view of a turntable, with one element of the automatic mold opening and closing means located adjacent to the table and with the other element of said means shown directly connected with the movable cope of the mold having a long angular arm for spanning the drag of the mold and having a terminal projection for engaging the inclined groove of said opening and closing means. Fig. 2 is a side elevational view of the automatically mold operating means, showing in this view, the mold in a closed position, upon the turntable. Fig. 3 is a similar view, showing the two-part mold, in an open position as well as the angular arm of the opening and closing means in its shifted position; and Fig. 4 is a side elevation view of the inner side of one of the mold opening and closing means, showing in dotted outline the manner in which the terminal projection of the angular arm enters and rides the inclined groove of said means in parting the movable cope from the sta-

tionary drag of the mold to permit of the removal then of the cast structure from said mold.

Referring to the drawings 5, is a turntable containing as illustrated a series of twelve molds thereon and each composed of a movable cope 6, and a stationary drag 7, hinged to each other at 8. The type of mold illustrated for particularly casting metal pipe forms the subject-matter of Letters Patent 65 granted to me under date of May 12th, 1908, and No. 887,070. The turntable 5, is arranged to travel along rails 9, by any suitable impelling means, not shown. Adjacent to the table 5, and track 9, in the foundation, 70 are located stationary blocks or frames 12 and 13, having on the inner side of each an inclined groove 14, with preferably wide flaring mouths 16 and 17, as clearly shown in Fig. 4, and which stationary blocks with respect to their functions as an element of said mold opening and closing means automatically operating, will be hereinafter more fully described.

To each movable cope 6, of the mold provided with a stationary drag 7, at one extremal portion of the same is rigidly secured an arm 18, the angular extension 19, of which is arranged to span or embrace the drag 7, of the mold as clearly shown in Fig. 3, with the movable cope 6, parted from the stationary drag 7, in which condition the cope 6, by the extension 19, of the arm 18, abutting against the underside of the drag 7, is held in a fixed open position. The terminal projection 20, of the extension 19, by which time will have ridden along the groove 14, of the stationary block 13, to thereby permit of the release of the cast structure from the mold after being cast. The direction of travel of the terminal projection 20, in such instance is indicated by the arrows in Fig. 4, with the two-part mold by such time having assumed the position shown in Fig. 3, with the cast structure in such a condition as to permit of removal of the same therefrom.

The stationary block 12, is reversely arranged with respect to the block 13, as to the groove thereof, so that the terminal 105 projection 20, of an angular arm 19, of a mold by riding in a downward direction in the inclined groove of the block 12, will close the mold and the angular arm 19, will assume the position illustrated in Fig. 2, with 110

the cope 6, closed against the stationary drag 7, of the mold ready to receive molten metal from the cupola furnace for the formation therein of the cast structure, as required. 5 By this arrangement of the arm 18, with its angular extension 19, connected with each movable cope of a mold it is entirely practicable to open and to close the mold by the same movement of the table 5, to produce in succession forward and reverse movements of the cope 6, without noise, jar or shock to the mold. This is important in pipe making or casting operations in which an internal core is employed to avoid cracking or breakage thereof.

Having thus described the nature and object of my invention what I claim as new and desire to secure by Letters Patent is:—

1. Means of the character described, comprising stationary inclined grooved blocks, in combination with a table provided with molds, each consisting of a cope and a drag and angular projecting means connected with each cope to open and close successively 20 by the same movement of the table a cope against a drag of each of said molds, substantially as and for the purposes described. 25

2. Means of the character described, comprising stationary inclined grooved blocks, in combination with a table provided with molds, each having a movable member and a fixed member and angular arms having terminal projections, said arms being secured to said movable member and in spanning the fixed member adapted to part the movable member from the fixed member, substantially as and for the purposes described.

3. Means of the character described, comprising stationary inclined grooved blocks, in combination with a table provided with molds, each having a movable member and a fixed member and angular arms having terminal projections, said arms being secured to said movable member and in spanning said fixed member holding said movable member in a fixed open position, substantially as and for the purposes described.

In witness whereof, I have hereunto set my signature in the presence of two subscribing witnesses.

EDGAR ALAN CUSTER.
